Attorneys

UNITED STATES PATENT OFFICE.

EMIL OLSON, OF ROCKFORD, ILLINOIS.

WAGON-BODY.

1,237,946.

Specification of Letters Patent. Patented Aug. 21, 1917.

Application filed January 25, 1917. Serial No. 144,442.

To all whom it may concern:

Be it known that I, EMIL OLSON, a citizen of the United States, residing at Rockford, in the county of Winnebago and State 5 of Illinois, have invented certain new and useful Improvements in Wagon-Bodies; and I do hereby declare the following to be a full, clear, and exact description of the invention, such as will enable others skilled in 10 the art to which it appertains to make and use the same.

The present invention relates to improvements in wagon bodies, and consists more particularly in an improved wagon body of 15 the type set forth in my similarly entitled prior Patent No. 1,099,718, granted June 9, 1914.

It is an object of the present invention to provide an improved wagon body constructed with a dump bottom comprising sections hung on hinges of improved design, adapted to permit free operation of said sections and to mount the same so as to be readily removed and replaced.

25 Another object of the present invention resides in providing novel and improved mechanism for operating the bottom sections, and for effectually retaining the same in closed position to carry the load.

30 It is a further object of the present invention to provide, in conjunction with the above-mentioned features, an improved tail-gate pivoted to swing down into horizontal position flush with the floor of the wagon box, and associated with means for maintaining the same in either elevated or lowered position, as required.

With these and other objects in view the invention consists in the novel details of 40 construction and combinations of parts more fully hereinafter disclosed and particularly pointed out in the claims.

In the accompanying drawings forming a part of this application, and in which 45 similar reference symbols indicate corresponding parts in the several views:

Figure 1 is a side elevational view of an improved wagon body constructed in accordance with the present invention.

50 Fig. 2 is a longitudinal sectional view of the same.

Fig. 3 is a top plan view of the improved body.

Fig. 4 is a transverse sectional view illustrating the bottom in closed position; and

Fig. 5 is a similar view with the bottom sections opened to release the load.

Referring more particularly to the drawings, 1 and 2 designate the sides of the improved wagon body, the same being assembled on transverse sills 3 and 4 and connected by ends 5 and 6.

A longitudinal sill 7, preferably of angle iron construction, is supported centrally by the transverse sills 3 and 4, and the wagon 65 bottom is constituted of a plurality of sections 8 and 9 mounted in pairs to either side of said longitudinal sill 7. To each of the sections 8 and 9 of the wagon bottom is secured a wear plate 10, extended beyond the 70 section and bent to form a hook 11 providing hinge connection with the wagon body. The hooks 11 of each of the central sections 8 are engaged through slots in the longitudinal sill 7, as disclosed to advantage in 75 Figs. 4 and 5; while the hooks of the lateral sections 9 are engaged with the lower ends of metallic strips 12, secured to the wagon sides 1 and 2.

The wear plates 10 are further provided 80 with projections 13, fitted to slide in grooves 14 formed in transversely disposed yokes 15, preferably of malleable metal, which latter embrace the sides 1 and 2 of the wagon box and are connected to lugs 16 projecting from 85 bent levers 17, the same being slotted, as indicated at 18, and slidably mounted over pins 19 secured to the wagon box.

The several levers 17 are connected together by links 20, and are arranged to be 90 actuated by rods 21 from arms 22, on the outer ends of a rock shaft 23. Two ratchets 24 and 25, with oppositely disposed teeth, are fixed to said rock shaft 23, one ratchet, 24, being operated by a foot lever 35, while 95 the other ratchet, 25, is associated with a handle 36. The ratchet teeth and handle and foot lever are so related that the depressing of the foot lever 35 will operate to dump the load; while the bottom sections are 100 returned to closed position by operation of the handle 36.

As disclosed to advantage in Figs. 1 and 2, the tail-gate 6 is pivoted, as indicated at 26, to permit the same to be moved down and 105 occupy a substantially horizontal position flush with the floor of the wagon body. To the outer end of the tail-gate 6 are secured fastenings 27 for holding the gate in the upper position shown in Figs. 1 and 3, and 110

adapted to engage irons 28 secured to the sides 1 and 2, upon which said tail-gate may be supported when moved to the horizontal position shown in Fig. 2. 37 and 38 are 5 braces rising from the cross sills 3 and 4, or other parts; and 39 is a foot board.

The parts are normally in the position shown in Figs. 1, 3 and 4, where the sections 8 and 9 are elevated to form a continuous bottom, and the tail-gate 6 is in raised position to inclose the wagon body. When the load is to be deposited, the foot lever 35 is depressed, and engaging with its ratchet 24 oscillates the rock shaft. The arms 22 are 15 thereby swung from the position shown in Fig. 1 to that indicated in Fig. 2, and the various levers and bottom sections moved correspondingly, so that the load is released.

To raise the bottom sections 8 and 9, the 20 handle 36 is grasped and lifted, it thus engaging its ratchet 25 and turning the rock shaft 23 in the opposite direction back to initial position.

It will be understood that from the construction of the hooks 11 and their connections with the wagon body, the sections 8 and 9 of the bottom may be freely raised and lowered without liability of the same becoming accidentally detached; but which 30 permit said sections to be readily removed and replaced, as found desirable or necessary.

It is obvious that those skilled in the art may vary the details of construction and arrangements of parts without departing from the spirit of my invention, and therefore I do not wish to be limited to such features except as may be required by the claims.

I claim:

40 1. A wagon body including a bottom composed of sections, wear plates secured to the under sides of said sections and being extended beyond such sections, hooks bent from the extended ends of said wear plates, 45 said hooks having a hinged connection with the wagon body, a yoke arranged beneath said sections and having a transverse groove therein, means for actuating said yoke to close the bottom sections and to drop down 50 to permit such sections to open, and projections on said wear plates received in the groove in said yoke, substantially as described.

55 2. A wagon body including sides, ends, a central longitudinal sill having slots along

its edges, bottom sections disposed to both sides of said sill, wear plates attached to the under sides of said sections and extended outwardly therebeyond, hooks bent from the outer ends of said wear plates, the hooks of 60 the inner sections being hingedly engaged through the slots in said central sill, strips secured to said sides, the hooks of the outer sections being hingedly engaged with the lower ends of said strips, projections on said 65 wear plates, yokes embracing said bottom sections and having transverse grooves for receiving said projections, and means for raising and lowering said yokes, substantially as described. 70

3. An improved wagon body including a bottom comprising a plurality of hinged sections, movable yokes for closing said sections, levers fulcrumed on the wagon body for actuating said yokes, a rock shaft journaled in the wagon body and connected to 75 actuate said levers, a foot lever for oscillating said rock shaft, and a handle for returning said rock shaft, substantially as described. 80

4. A wagon body including a bottom comprising a plurality of hinged sections, yokes for supporting and operating said sections, levers connected to said yokes and fulcrumed on the wagon body, a rock shaft journaled 85 in said wagon body, arms on said rock shaft, connections between said arms and said several levers, a foot lever for actuating said rock shaft to dump the load, and a handle for revolving the rock shaft to return the 90 sections to closed position, substantially as described.

5. An improved wagon body including a bottom comprising a plurality of sections hinged to said wagon body, grooved yokes 95 embracing said sections, projections on said sections slidably fitted in the grooves in said yokes, slotted levers fulcrumed on said wagon body and connected to actuate said yokes, a rock shaft journaled in said wagon 100 body, arms on the ends of said rock shaft, rods for connecting said arms to actuate said several levers, and means for actuating said rock shaft, substantially as described.

In testimony whereof, I affix my signature. 105

EMIL OLSON.
